UNITED STATES PATENT OFFICE.

MARTIN C. MCKENNEY, WILLIAM H. SWAN, AND FRANK J. PEACOCK, OF SAN BERNARDINO, CALIFORNIA, ASSIGNORS TO SANITARY UTILITIES COMPANY, OF SAN BERNARDINO, CALIFORNIA, A CORPORATION OF CALIFORNIA.

SANITARY CHURN.

1,148,786.

Specification of Letters Patent. Patented Aug. 3, 1915.

Application filed July 27, 1914. Serial No. 853,470.

To all whom it may concern:

Be it known that we, MARTIN C. MCKENNEY, WILLIAM H. SWAN, and FRANK J. PEACOCK, all citizens of the United States, 5 residing at San Bernardino, in the county of San Bernardino and State of California, have invented certain new and useful Improvements in Sanitary Churns, of which the following is a specification.

10 This invention relates to improvements pertaining to the sanitary churn patented to Sanitary Utilities Company of San Bernardino, California, a corporation of California, upon an application filed by Charles 15 De Forest, patented November 4, 1913, No. 1,077,456.

Objects of this invention are: simplified construction, increased convenience of assembling and disassembling and improved 20 security against leakage.

Other objects and advantages may appear from the subjoined detail description and the drawings referred to.

The accompanying drawings illustrate the 25 invention.

Figure 1 is a perspective view of the improved churn ready for use. Fig. 2 is a broken axial sectional elevation of the same. Fig. 3 is a view of one of the end supports 30 detached. Fig. 4 is an enlarged view of one of the journal boxes detached.

The end members or supports 1, 2 of the stand are duplicates, each being constructed of strap iron or the like bent sidewise at the 35 ends to form feet 3 that may have holes 4 therein to receive fasteners, not shown, and bent edgewise at the middle to form journal box supports 5 pierced with holes 6 to receive rivets 7 which fasten journal boxes 40 8, 8', to the journal box supports. Each journal box comprises a tubular portion 9 and lug 10, said lug being flat to fit against the strap and pierced with holes 11 corresponding to the holes 6 in the bend of the 45 strap. The flat lug 10 is spaced from the inner end of the box a distance slightly greater than the thickness of the end support so that when the flat lug is riveted or otherwise fastened to the outer face of the 50 end support, the box will project slightly beyond the inner face of such support. Said end supports are connected together by spacing bars 12 that may be fastened by any suitable means as rivets or bolts to the 55 end supports a suitable distance above the

feet thereof. In the present instance bolts and nuts 13 are shown in order that the frame may be readily taken apart and assembled together.

The journal boxes are alined with each other and are duplicates excepting that the outer end of one of said boxes is provided with a notch 14 to receive a pin 15 to fasten the vent tube 16 in place to keep it from turning.

The swing is composed of a strap bent to form a bottom piece 17, and side pieces having straight lower limbs 18, an outward bend 19 and straight upper limbs 20; said upper limbs being provided near said outward bends with outwardly extending tubular journals 21, 22; one of said journals 21 having an outwardly extending tubular portion 23 and being transversely pierced at 24 to receive a pin 25 to fasten in said journal 75 the axis of a crank 26 which has a hole 27 corresponding with the hole 24 of the journal. In the other journal 22, the bore 28 extending axially therethrough and through the upper limb 20 of the swing is for the 80 purpose of receiving the straight limb 29 of the vent tube 16 which is provided with a flange 30 to contact with one or more washers 31 of suitable solid material to compress a yielding gasket 32, preferably 85 made of sponge rubber, against the inside of the container 33 which is preferably a glass jar provided inside above its center of gravity with a socket formed by an outwardly extending boss 34 pierced with a 90 hole 35 through which the straight limb 29 of the vent tube may be inserted from the inside of said jar and thence through the tubular journal box 22. Said socket serves as a seat for the gasket 32 so as to hold the 95 limb 29 of the vent tube against the shifting relative to the axis of the boss. The stem of said vent tube is transversely pierced with a hole 36 to receive a pin 15 which also enters notches 14, thus to keep the curved 100 inlet end uppermost and the open inner mouth down.

The straight upper limbs 20 of the swing extend somewhat above the journals 21, 22 and a bail 37 also constructed of strap iron or the like is pivoted to the upper end of said upper limbs by pivots 38 which may be riveted in place, as shown. The center of the bail is provided with an upwardly extending boss 39 internally screw-threaded to 110

receive the thumb screw 40 which is designed to act against the knob 41 of the glass cover 42 that is placed upon a gasket 43 and compressed thereon by the screw as with 5 said former patent. The swing is further provided with a U bar 44, having at its middle a bend 45 and being fastened by a rivet 46 to the middle of the bottom member of the swing. The upright end limbs of 10 the U bar 44 receive the lower ends of the container 33 to hold the container in true position.

In practice the container is easily inserted into the swing when the bail 39 is thrown down for that purpose. The boss 34 on the jar when the jar is seated in the swing is at 15 the level of the axis of the journals and the jar when placed on the swing is turned to bring the boss into axial alinement with the 20 journals, whereupon the straight limb 29 of the vent tube is inserted inside of the jar to bring the rubber gasket into compression against the inside of said jar and the straight limb is pushed through far enough 25 to allow the pin 15 to be inserted through the hole and then the vent tube is allowed to be resiliently retracted by the gasket to bring the pin into the notch. Then the jar is filled to some point below the top bend 30 of the vent tube, which tube is bent over correspondingly to the tube shown in the De Forest patent. Then the rubber gasket 43 for the mouth of the jar is put into place, 35 the glass cover is placed on the top of the gasket, the bail is then brought into alinement with the swing and the thumb screw 40 is then screwed down onto the knob 41 of the cover, thus to not only compress the gasket but also to put the sides of the bail and the 40 swing under a tension that springs the upper projections of the swing inward until the lower ends of the bail where they are pivoted to such upper projections press firmly but resiliently against the sides of the 45 jar, thus firmly holding the jar friction-tight in the swing and relieving the boss from any strain thereon other than the yielding pressure of the gasket, the hole through the boss being of greater diameter 50 than the vent tube so that the boss does not touch the vent tube but is pressed by the rubber against the upper straight limb of the swing. The crank being fastened in place by its pin may then be turned, thereby 55 rotating the swing and bail and the container, care being taken that the rotation be sufficiently slow to allow the milk to fall from end to end of the container at each half revolution. By turning the crank for 60 about twelve minutes, more or less, the churning will be completed.

The churn may be made of any desired size and it is understood that the container

may be made of various material, glass being preferred for visual and sanitary purposes. The vent tube and washers may be made of aluminum or other suitable material not liable to corrosion from the contents of the churn. 65

When the churning has been completed 70 the thumb screw will be unscrewed, the jar cover and its gasket removed and then the crank may be turned to tilt the container to pour off the buttermilk, after which, a charge of cold water may be put into the 75 container and the container again closed and operated to wash the butter; after which the cover may be removed, the water poured off by tilting the container and then the butter removed; whereupon by pressing 80 the vent tube outward the pin 38 may be withdrawn, thus releasing the vent tube which is then taken out. Then the container may be removed from the swing and all the parts may be thoroughly sterilized. 85

We claim:

1. In a churn, a swing provided with journals, boxes for said journals, one of said journals being tubular, a container mounted in the swing and provided inside and outside respectively with a socket and an outwardly extending boss alined with the tubular journal, said boss being perforated, a vent tube having a flange and inserted through the boss and journal, a soft gasket 95 seated in said socket and compressed between the flange and inside of the container, and means engaging the vent tube to hold it against endwise movement.

2. In a churn, the combination with a 100 swing having yielding upper extensions, of a container seated in the swing, a resilient bail pivotally connected to the inner sides of the upper extensions, and a screw screwing through the bail and drawing the bail up to 105 yieldingly hold the lower end of the bail against the container.

3. The combination with a swing having upward extensions above its axis, of a container in the swing, a resilient bail pivoted 110 to the upper ends of the upper extensions of the swing, a cover to the container, and means at the center of the bail to hold said cover in place and to spring the bail to draw its sides in to compress them against the 115 container.

In testimony whereof, we have hereunto set our hands at San Bernardino, California, this 18th day of July, 1914.

MARTIN C. MCKENNEY.
